SPLASH GUARD FOR MOTOR VEHICLES

Robert Podall, Northbrook, Ill., assignor to Jeffrey Allan
Industries, Inc., Evanston, Ill.

Filed Oct. 31, 1975, Ser. No. 627,507

Term of patent 14 years

Int. Cl. D12—16

U.S. Cl. D12—185

FIG. 3

FIG. 2

FIG. 1

FIG. 1 is a front elevational view of a splash guard for motor vehicles showing my new design;

FIG. 2 is a side elevational view thereof; and
FIG. 3 is a rear elevational view thereof.

I claim:

The ornamental design for a splash guard for motor vehicles, as shown.
